WHEEL

Thomas L. Hibbard, Birmingham, Mich., assignor to Kelsey-Hayes Company, Romulus, Mich., a corporation of Delaware

Filed May 24, 1965, Ser. No. 85,424

Term of patent 14 years

(Cl. D14—30)

FIG. 2 is a cross sectional view thereof taken along the line 2—2 of FIG. 1; and

FIG. 3 is a reduced scale perspective view thereof with the broken lines omitted for convenience of illustration.

The dominant features of my design are shown in solid lines.

I claim:

The ornamental design for a wheel, substantially as shown and described.
